DESIGN.

S. J. SHIELS.

MISS'S COSTUME.

Patented Nov. 25, 1884.

No. 15,579.

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 15,579, dated November 25, 1884.

Application filed September 12, 1884. Term of patent 3½ years.

To all whom it may concern:

Be it known that I, SARAH JANE SHIELS, of the city, county, and State of New York, have invented and produced a new and original 5 Design for a Pattern of a Miss's Costume, (numbered 9,405,) and I do hereby declare that the engraved prints accompanying this specification convey to any one accustomed to using paper patterns a clear understanding of 10 how a garment made up by the pattern will appear.

The design shows a walking-skirt and a basque. The skirt exhibits a side-plaited drapery extending across the front and left 15 side and falling even with the lower edge; two short front draperies that appear to underlap one another at the right side, the right drapery displaying plaits in its front and back edges, and the left drapery displaying plaits in

its front edge and gathers in its back edge, 20 and a full back drapery falling in straight folds to the lower edge of the skirt. The basque exhibits a closely-fitted front outlining a deep point at the lower end of the closing, and a high arch over the hips, a close-fitted back falling in a deep square outline and displaying undersolded plaits at the lower 25 ends of its middle three body-seams, coat-sleeves, and a standing collar.

What I claim as my invention, and desire to 30 secure by Letters Patent, is—

The design for a miss's costume, as shown in the engraved prints accompanying this specification.

SARAH JANE SHIELS.
